INTERMEDIATES IN THE CONVERSION OF
11-KETODIOSGENIN TO CORTISONEEdward S. Rothman, Philadelphia, and Monroe E. Wall,
Oreland, Pa., assignors to the United States of America as represented by the Secretary of Agriculture
No. Drawing. Filed Mar. 5, 1957, Ser. No. 644,184

5 Claims. (Cl. 260—397.45)

(Granted under Title 35, U.S. Code (1952), sec. 266)

A non-exclusive, irrevocable, royalty-free license in the invention herein described, throughout the world for all purposes of the United States Government, with power to grant sublicenses for such purposes, is hereby granted to the Government of the United States of Amer-

atom in order to obtain the desired Δ^4 -3 ketone system possessed by cortisone.

Evans et al., J. Chem. Soc. (London) (1956) 4356, in discussing the difficulties of the multiple step insertion of the Δ^4 double bond obtained only a 10% conversion by the standard methods for this operation. By newer improvements, Evans et al., raised the yield of crude cortisone acetate to 50% for the four steps of the operation, but even so, purification (by Girard's reagent) of their crude cortisone acetate product further halved their yield.

The advantage of our process lies in the avoidance of these multiple, low-yielding steps.

Our invention will now be described with reference to 15 the following diagrams:

FLOW SHEET OF CHEMICAL TRANSFORMATION

ica. In co-pending patent applications Serial Numbers 566,737, filed February 20, 1956, now U.S. Patent 2,830,986 and 644,183, filed March 5, 1957, now U.S. Patent 2,899,428, steroid sapogenins gentrogenin and its C-25 diastereoisomer correlogenin were described and were converted to the new steroid sapogenin, 11-keto diosgenin. When 11-keto diosgenin is converted to cortisone via 11-keto tigogenin, the advantages of its olefinic functional group are wasted in so doing. It is the purpose of the present disclosure to show that 11-keto diosgenin can be converted to cortisone via a new route involving new intermediates in which full advantage of the naturally occurring 3-hydroxy 5,6-olefinic functional group system can be made. Among the advantages of the 3-hydroxy 5,6-olefinic system is the ease with which it can be converted in a one step, high-yield Oppenauer oxidation to the Δ^4 -3 ketone system necessary for the physiological adrenal cortical hormone activity of cortisone. This one step conversion contrasts with the multiple operations necessary in converting the 11-keto tigogenin derivative to the Δ^4 -3 ketone system in the commercial processes. These multiple operations involve (1) oxidation to the saturated 3-ketone, (2) dibromination at the 2 and 4 positions, (3) reaction with sodium iodide to simultaneously metathetically replace the C-2 bromine atom with an iodine atom and establish a $\Delta^{5,6}$ bond and (4) finally to reductively remove the iodine

50 In our process we degrade 11-keto diosgenin acetate, I, by a process well-known to those familiar with the art to the new compound 3 β -acetoxypregnadiene-11,20-dione, II. It is neither desirable or necessary to isolate intermediates in the course of this transformation of sapogenin to pregnadiene. The product, isolated in 55% yield or better, is treated with alkaline hydrogen peroxide to selectively epoxidize only the 16-17 olefinic bond to form 3 β -acetoxypregnene-16 α ,17 α -epoxy-5,20-dione, III, in 84% yield. The product is saponified in nearly 55 100% yield to 16 α ,17 α -epoxy-3 β -hydroxy-5-pregnene-11,20-dione, IV. Treatment of this material with hydrobromic acid followed by Raney nickel debromination produces 3 β ,17 α -dihydroxy-5-pregnene-11,20-dione, V, in 70% yield for the two steps. This material is formylated at the C-3 hydroxy group in 80% yield to give 3 β -formyloxy-17 α -hydroxy-5-pregnene-11,20-dione, VI. Treatment of the formate with one molar equivalent of bromine would be expected to saturate the 5,6-olefinic bond since, 60 in general, addition reactions are more rapid than substitution reactions. Surprisingly, this expected reaction of double bond saturation does not occur to any major extent. Instead substitution on the C-21 methyl group occurs. Lowered yields are obtained if more than one mole of bromine is added; therefore, excess bromine is 65 to be avoided. Treatment of the bromination product with sodium iodide followed by a subsequent, separate 70

treatment with sodium or potassium acetate gives the diester, 21-acetoxy-3 β -formoxy-17 α -hydroxy-5-pregnene-11,20-dione, VII. Acetylation of this compound either by long refluxing with acetic anhydride or by 18-hour treatment at room temperature with an acetylation catalyst such as p-toluene sulfonic acid or perchloric acid gives 17 α ,21-diacetoxo-3 β -formoxy-5-pregnene-11,20-dione, VIII. In the course of isolation some hydrolytic loss of formate sometimes occurs to form 17 α ,21-diacetoxo-3 β -hydroxy-5-pregnene-11,20-dione, IX, but this offers no disadvantage since both 3 β -hydroxyl group and the 3 β -formoxyl group behave alike to the mildly alkaline aluminum isopropoxide Oppenauer reagent, and form the same 3-ketone. This Oppenauer oxidation product of the 3-formate or of the 3-hydroxyl compound or of their mixtures produces the known cortisone 17 α ,21-diacetate, X. All compounds preceding cortisone 17 α ,21-diacetate in this series of transformations are new compounds not previously described. Hydrolysis of cortisone diacetate produces cortisone, XI, an important hormone of known utility.

EXAMPLE I

Degradation of 11-keto diosgenin acetate.—In a 250 ml. thick glass bottle fitted with a wired-on, gas-tight, ground-glass stopper were placed 14.5 g. of 11-keto diosgenin acetate, I, 37 ml. of acetic anhydride, and a trace of acetic acid. The flask contents were heated for 4 hours at 180° C., were cooled, diluted with 74 ml. of acetic acid and 6 ml. of water. Thereafter the conditions of procedure A, J. Am. Chem. Soc. 77 5665 (1955), for the oxidative cleavage and alkaline hydrolysis of diosgenin acetate of Wall et al., were followed to give 3 β -acetoxy-5,6-pregnadiene-11,20-dione, II, 6.16 g., M.P. 183–186° C. (from hexane), $[\alpha]_D^{25} = -1.7^\circ$,

$\lambda_{\text{Max}}^{\text{MeOH}}$ 234 m μ .

log $\epsilon = 3.93$. The mother liquors from this preparation were also used since they gave crystalline epoxide when treated as in Example 2. The total yield of crystalline product was 55 mole percent.

Calcd. for C₂₃H₃₀O₄: C, 74.56; H, 8.16. Found: C, 74.36; H, 8.33.

When the product was crystallized from methanol a molecule of solvent was bound to each molecule of steroid by solvation.

EXAMPLE II

3 β -acetoxy-16 α ,17 α -epoxy-5-pregnene-11,20-dione.—A 5.95 g. sample of the preceding preparation was dissolved in 800 ml. of methanol at 10° C., 5 ml. of 30% hydrogen peroxide and 2.3 ml. of 4 N sodium hydroxide were added and the mixture was stored overnight. A crystalline water-insoluble precipitate formed and was filtered off. The filtrate was diluted with an equal volume of water and a new crop crystals formed and were filtered off. The filtrate was neutralized with hydrochloric acid and was well-extracted with methylene chloride which was evaporated to give a glassy residue. All solids were combed and converted to acetates by dissolving in 30 ml. of pyridine and 10 ml. of acetic anhydride and heating 0.75 hour on the steambath. On dilution with water and isolation by ether extraction 5.1 g. of ethanol recrystallized product were obtained (84% yield). The product was freed of 100 mg. of an unidentified extremely insoluble material (M.P. 318°) by solution in ethyl acetate, filtering and crystallizing by evaporation to dryness. The product melted from 205–206° C. forming dense polyhedra undergoing transition on the Kofler block to refractile, tetragonal prisms, 70 $[\alpha]_D^{25} = +14.8$.

Calcd. for C₂₃H₃₀O₅: C, 71.48; H, 7.82. Found: C, 71.46; H, 8.08.

Saponification with 5% methanolic potassium hydrox-

ide gave 4.46 g. of 16 α ,17 α -epoxy-3 β -hydroxy-5-pregnene-11,20-dione, IV, M.P. 111° to about 114° when crystallized from ethanol. Perhaps the molecule thus crystallized is solvated but the lower indicated melting temperature is characteristic.

Calcd. for C₂₁H₂₈O₄: C, 73.22; H, 819. Found: C, 73.98; H, 8.01.

EXAMPLE III

3 β ,17 α -dihydroxy-5-pregnene-11,20-dione.—To a solution of 2.22 g. of 16 α ,17 α -epoxy-3 β -hydroxy-5-pregnene-11,20-dione, IV, in 22 ml. of acetic acid was added 4.3 ml. of a 40% solution of hydrogen bromide in acetic acid. After standing for 25 minutes the reaction mixture was poured into 140 ml. of cold water and the precipitated bromohydride was filtered off and air dried. Ten grams of Raney nickel was heated with 100 ml. of refluxing acetone. Ten ml. of water, two ml. of acetic acid, and the crude bromohydride were added and stirring and heating under reflux was maintained for 4 hours. The acetone solution was decanted and evaporated to dryness in vacuo. Crystallization of the residue from methylene chloride and from ethylacetate gave 1.57 g. (71% yield) of 3 β ,17 α -dihydroxy-5-pregnene-11,20-dione, V. The compound formed dense polyhedral crystals, M.P. 277–278° C. after transition over 220° to lance forms $[\alpha]_D^{25} = +6^\circ$ (MeOH).

Calcd. for C₂₁H₃₀O₄: C, 72.80; H, 8.73. Found: C, 72.41; H, 8.69.

EXAMPLE IV

3 β -formoxy-17 α -hydroxy-5-pregnene-11,20-dione.—The diol of the preceding preparation, 1.45 g., was dissolved in 35 ml. of 90% formic acid and heated to 65° for two hours. The solution was poured into a large volume of cold water containing sodium chloride and sodium formate and the precipitated solids were filtered off and washed with water. Recrystallization from methanol gave 3 β -formoxy-17 α -hydroxy-5-pregnene-11,20-dione, VI, as thick scales, M.P. 255–260° C. after transition on the Kofler block to overlapping thin scales covering the entire field. The yield was 80%.

EXAMPLE V

21-acetoxy-3 β -formoxy-17 α -hydroxy-5-pregnene-11,20-dione.—The preceding formate 1.253 g. (0.00334 mole) was dissolved in 25 ml. of dry methylene chloride and the solution was treated with 13.32 ml. of a solution of bromine (0.00334 moles) in 13.32 ml. of methylene chloride. The volume was reduced by distillation in vacuo at 30°; the solution was washed with 1% sodium hydrogen carbonate solution; and the solvents removed in vacuo. The residue was dissolved in acetone, 25 ml. and 2 g. of sodium iodide were added. The mixture was let stand overnight and was then poured into a cold solution of 2 g. of sodium thiosulfate in 70 ml. of water. The steroid was filtered off and dried in vacuo at room temperature. The crude iodo compound was dissolved in 25 ml. of dry acetone, 2.5 g. of potassium acetate was added and the mixture was heated under reflux and with stirring for 18 hours. The reaction mixture was cooled, poured into water and the steroid was isolated by extraction with ether. Evaporation of the ether in vacuo gave a colorless solid foam. Chromatography of this material with chloroform elution gave only 540 mg. of the desired crystalline, 21-acetoxy-3 β -formoxy-17 α -hydroxy-5-pregnene-11,20-dione, VII, M.P. 192.5–193.5°, red melt, $[\alpha]_D^{25} = +20.8$, but the colorless glassy residues eluted just after the crystalline material gave 100 mg. of the 17 α acetoxy derivative, VIII, when treated as in Example VI.

Calcd. for C₂₄H₃₂O₇: C, 66.65; H, 7.46. Found: C, 66.41; H, 7.144.

EXAMPLE VI

17 α ,21-diacetoxo-3 β -formoxy-5-pregnene-11,20-dione.—The preceding compound, 99 mg., in 0.71 ml.

of acetic anhydride was treated with 31.4 mg. of p-toluene sulfonic acid at room temperature overnight. On decomposing with water an amorphous solid was obtained which on chromatography on Florisil gave 80 mg. of crystallizable material. The earlier benzene-eluted 17α , 21 - diacetoxy - 3β - formoxy - 5 - pregnene - 11,20-dione, VIII, $[\alpha]_D^{25} = +40^\circ$ melts with decomposition from 228 to 229°, occasionally from 233 to 235°, and shows no hydroxyl band in the infrared spectrum, a broad multiple ketonic band and a series of ester bands at 1237, 1250, and 1260 cm^{-1} . The chloroform eluate gave 17α ,21-diacetoxy- 3β -hydroxy-5-pregnene-11,20-dione, IX, M.P. 203-205° C., $[\alpha]_D^{25} = +83^\circ$ showing infrared hydroxyl bands at 3410 and 3500 cm^{-1} (KBr disc), broad ketone bands centered at 1705 and 1731 cm^{-1} and a strong, sharp ester band centered at 1258 cm^{-1} with a small band at 1245 cm^{-1} . Non-crystallizable mother liquor residues were saved and carried through the Oppenauer oxidation reaction indicated in Example 7.

Compound VIII, calcd. for $\text{C}_{26}\text{H}_{34}\text{O}_8$: C, 65.80; H, 7.22. Found: C, 65.50; H, 7.21.

Compound IX, calcd. for $\text{C}_{25}\text{H}_{34}\text{O}_7$: C, 67.24; H, 7.68. Found: C, 67.02; H, 7.60.

EXAMPLE VII

Cortisone 17 α ,21-diacetate and cortisone.—Eight hundred milligrams of the uncryallized mother liquor residues from Example 6 consisting essentially of a mixture of the 3-hydroxy and 3-formoxyl compounds were dissolved in 25 ml. of dry toluene. Eight ml. of cyclohexanone and 840 mg. of aluminum isopropoxide were added and the mixture was refluxed for 0.75 hour, cooled and water was added. The contents of the flask were heated until organic solvents were lost, and the gummy solid was collected by extraction with ether. Evaporation of the ether in vacuo and crystallization of the residue from methanol gave 400 mg. of cortisone, 17 α ,21-diacetate, X, M.P. 220-221°,

$\lambda_{\text{Max}}^{\text{MgOH}} 238 \text{ m}\mu$

$\epsilon = 35,000$, identical with an authentic specimen. Hydrolysis of cortisone diacetate in 5% sodium hydroxide in

methanol gave an 80% yield of cortisone, XI, identical with an authentic specimen.

EXAMPLE VIII

5 Two hundred milligrams of crystalline, 17 α ,21-diacetoxy 3β -formoxy-5-pregnene-11,20-dione, VIII, in 20 ml. of dry toluene, 300 mg. aluminum isopropoxide and 2 ml. of cyclohexanone were refluxed for 45 minutes. Water, 100 ml., was added and the two-phase mixture was boiled until all organic solvents had been carried off in the vapors. The residue was collected as a pasty mass by decantation of the water. Crystallization from methanol gave a 75% yield of cortisone, 17 α ,21-diacetate, X.

We claim:

- 15 1. $3\beta,17\alpha$ -dihydroxy-5-pregnene-11,20-dione.
2. 3β - formoxy - 17α - hydroxy - 5 - pregnene - 11,20-dione.
3. 21 - acetoxy - 3β - formoxy - 17α - hydroxy - 5 - pregnene-11,20-dione.
4. $17\alpha,21$ - diacetoxy - 3β - formoxy - 5 - pregnene-11,20-dione.
5. $17\alpha,21$ - diacetoxy - 3β - hydroxy - 5 - pregnene-11,20-dione.
